Fig. 3

Technical drawing of a circular component with various features labeled with 'd' and 'd⁶'.

The drawing shows a central rectangular area with a cross-hatched pattern. This central area is surrounded by a rectangular border. The border is further surrounded by a circular area containing two large, hatched circular features. The outermost boundary of the entire component is a circle.

Labels include:

- d^6 at the top center and bottom center.
- d^3 at the top center of the central rectangular area.
- d^2 at the top left and top right of the central rectangular area.
- d^8 at the bottom center of the central rectangular area.
- d^3 at the bottom center of the outer rectangular border.
- d^2 at the bottom left and bottom right of the outer rectangular border.
- d on the left side of the outer circle.

UNITED STATES PATENT OFFICE.

WILLIAM HUNTER EMERICK, OF OSAWATOMIE, KANSAS, AND PETER ALQUIST, OF MEMPHIS, TENNESSEE.

CAR-FRAME.

No. 851,230.

Specification of Letters Patent.

Patented April 23, 1907.

Application filed January 5, 1907. Serial No. 350,869.

To all whom it may concern:

Be it known that we, WILLIAM HUNTER EMERICK, a citizen of the United States, residing in Osawatomie, in the county of Miami and State of Kansas, and PETER ALQUIST, a citizen of the United States, residing in Memphis, in the county of Shelby and State of Tennessee, have invented a new and useful Improvement in Car-Frames, of which the following is a specification.

Our invention relates to improvements in car frames, and more particularly to improvements in means for removably connecting draft timbers or other parts to the center sills or other members of the car framework, and our present invention is an improvement upon the inventions forming the subject of our Patents Nos. 795,593 of July 25, 1905, and 819,047 and 819,048 of May 1st, 1906.

The object of our present invention, is to provide a simple, strong, efficient and durable construction of parts and devices for removably connecting together the draft timbers and center sills of a car or other parts or members of the car frame-work without the use of long connecting bolts extending through the sills and draft-timbers or other parts connected, and by means of which such parts may be very rigidly and firmly connected together, and at the same time the one readily removed from the other.

Our invention consists in the novel construction of parts and devices, and in the novel combinations of parts and devices herein shown and described, and more particularly specified in the claims.

In the accompanying drawing forming a part of this specification, Figure 1 is a side elevation partly in vertical longitudinal section showing a portion of a car frame to which our invention is applied. Fig. 2 is a vertical longitudinal section taken on the line 2-2 of Fig. 3; Fig. 3 is a vertical cross section on line 3-3 of Fig. 2. Fig. 4 is a detail vertical section on line 4-4 of Fig. 3. Fig. 5 is a cross section on line 5-5 of Fig. 4. Fig. 6 is a detail bottom view of the upper connecting plate and Fig. 7 is a detail plan view of the lower connecting plate. Figs. 6 and 7 show the meeting faces of the two connecting plates.

In the drawing, we have illustrated our invention as applied or used for removably connecting the draft timbers of a railway car

to the center sills thereof without the use of long connecting bolts extending through the draft timbers and center sills so that the draft timbers may be conveniently removed and replaced when required without interfering with the other parts of the car or its framework.

In the drawing, A represents the center sills and B the draft timbers or other parts or frame pieces to be removably connected. A¹ is the front or end sill, A² the buffer block, C the draw-bar, C¹ the side plates or stop castings of the draft rigging secured to the draft timbers B, C² the draft rigging springs and C³ the followers; these parts being all of any usual or customary construction.

D and D¹ are the upper and lower connecting plates, the former being rigidly secured by bolts F F to the center sill, and the latter by a bolt F¹ to the draft timber. Any desired number of pairs of connecting plates may be employed between each draft timber and its sill or the other parts to be connected. The connecting plate D has on its under side at each end a circular recess d to receive the head f of the short connecting bolt F, and the lower connecting plate D¹ has a central recess or depression d¹ in its upper face to receive the head of the short connecting bolt F¹ by which the plate D¹ is connected to the draft timber. The upper connecting plate D has on its lower face a plurality of holes d², preferably four in number and a pair of longitudinal flanges d³ between which the lower connecting plate D¹ fits.

The lower connecting plate D¹ has on its meeting face a plurality of lugs d⁴, preferably four in number which are preferably round in cross section, but slightly tapering or conical, and which fit in corresponding holes or recesses d⁵ in the upper connecting plate D. The longitudinal or side flanges d³ of the upper connecting plate D are furnished with transverse holes d⁶ registering with transverse holes d⁷ in the lower connecting plate D¹ through which holes the transverse connecting bolts G extend. By this improved construction, the transverse connecting bolts, it will be observed, extend through the body of one of the connecting plates instead of simply through lugs thereon and through continuous side flanges, which may be made of any length desired, instead of through short lugs on the other connecting plate,

thus adding materially to the strength, safety, security and rigidity of the union between the connecting plates and the draft timbers and sills or other members connected thereby.

The upper connecting block D is furnished with a recess d^8 , preferably about one quarter of an inch in depth, in which fits the lower connecting block D^1 so that the lower connecting block thus fits within the upper connecting block and thereby in part relieves the lugs on the lower connecting block from shearing strain.

The flanges d^3 on the inner side of the connecting blocks D are inwardly offset so that the side plates or stop castings C¹ of the draft rigging can, if desired, project above the draft timbers B and so that the heads of the connecting bolts G will not project beyond the inner faces of the draft timbers or center sills.

We claim:—

1. In a car frame, the combination with the center sills and draft timbers, of connecting plates secured to said sills and draft timbers respectively, said connecting plates secured to the sills having each at its ends bolt head recesses and short bolts connecting the same to the sills, and said connecting plates secured to the draft timbers having each at its middle a bolt head recess and a short bolt connecting the same with the draft timber, one of said connecting plates having on its meeting face longitudinally extending side flanges or ribs embracing the other plate, and said other connecting plate having on its meeting face a plurality of lugs entering holes or recesses in said first mentioned plate, and transverse connecting bolts extending through the body of one of said plates and the side flanges on the other, substantially as specified.

2. In a car frame, the combination with the center sills and draft timbers, of connecting plates secured to the said sills and draft timbers respectively, said connecting plates secured to the sills having each at its ends bolt head recesses and short bolts connecting the same to the sills, and said connecting plates secured to the draft timbers having each at its middle a bolt head recess and a short bolt connecting the same with the draft timber, one of said connecting plates having on its meeting face longitudinally extending side flanges or ribs embracing the other plate and said other connecting plate having on its meeting face a plurality of lugs entering holes or recesses in said first mentioned plate, and transverse connecting bolts extending through the body of one of said plates and the side flanges on the other, the interfitting lugs and holes on said plates being slightly tapering, substantially as specified.

3. The combination with two members to be removably connected together, of a pair

of connecting plates secured to said members respectively, one of said plates having side flanges embracing the other plate, and connecting bolts extending through said side flanges and the connecting plate embraced thereby, substantially as specified.

4. The combination with two members to be removably connected together, of a pair of connecting plates secured to said members respectively, one of said plates having side flanges embracing the other plate, and connecting bolts extending through said side flanges and the connecting plate embraced thereby, said plates having interfitting lugs and recesses, substantially as specified.

5. The combination with two members to be removably connected together, of a pair of connecting plates secured to said members respectively, one of said plates having side flanges embracing the other plate, and connecting bolts extending through said side flanges and the connecting plate embraced thereby, said plates having tapering interfitting lugs and recesses, substantially as specified.

6. In a car frame, the combination with a center sill and a draft timber, of a pair of connecting plates secured to said sill and draft timber respectively, short bolts connecting said plates to said draft timber and sill respectively, one of said plates having side flanges embracing the other plate and a bolt extending through said side flanges and the plate embraced thereby, substantially as specified.

7. In a car frame, the combination with a center sill and a draft timber, of a pair of connecting plates secured to said sill and draft timber respectively, short bolts connecting said plates to said draft timber and sill respectively, one of said plates having side flanges embracing the other plate and a bolt extending through said side flanges and the plate embraced thereby, said plates having interfitting lugs and recesses respectively, substantially as specified.

8. In a car frame, the combination with a center sill and a draft timber, of a pair of connecting plates secured to said sill and draft timber respectively, short bolts connecting said plates to said draft timber and sill respectively, one of said plates having side flanges embracing the other plate and a bolt extending through said side flanges and the plate embraced thereby, said flange on the inner side of said connecting plate being inwardly offset, substantially as specified.

9. The combination with two members to be removably connected together, of a pair of connecting plates secured to said members respectively, one of said plates having side flanges embracing the other plate, and connecting bolts extending through said side flanges and the connecting plate embraced thereby, one of said connecting plates having

a recess on its lower face within which the other connecting plate fits, substantially as specified.

10. In a car frame, the combination with the center sills and draft timbers, of connecting plates secured to said sills and draft timbers respectively, said connecting plates secured to the sills having each at its ends bolt head recesses and short bolts connecting the same to the sills, and said connecting plates secured to the draft timbers having each at its middle a bolt head recess and a short bolt connecting the same with the draft timber, one of said connecting plates having on its meeting face longitudinally extending side flanges or ribs embracing the other plate, and said other connecting plate having on its

meeting face a plurality of lugs entering holes or recesses in said first mentioned plate, and transverse connecting bolts extending through the body of one of said plates and the side flanges on the other, the upper connecting plate having a recess within which the lower connecting plate fits, substantially as specified. 20
